OTTO BOTHE, OF STEGLITZ, NEAR BERLIN, GERMANY.

DEVICE FOR ELECTRICALLY REPRODUCING SOUNDS.

Application filed March 23, 1922. Serial No. 546,106.

To all whom it may concern:

Be it known that I, OTTO BOTHE, a citizen of Germany, residing at Steglitz, near Berlin, Germany, have invented certain new and 5 useful Improvements in Devices for Electrically Reproducing Sounds, of which the following is a specification.

This invention relates to electrical sound-reproducing devices by which tones are reproduced without the slightest change of 10 their natural timbre while amplifying or increasing their loudness to any desired extent.

In the electrical reproduction of spoken words and musical notes, the electric waves produced are extraordinary complicated, because waves of the fundamental tone and the partial tones are superimposed on one another or form a combination wave. Hence, if the transmission is to render possible 15 a true reproduction of the speech or music the form of the wave resulting from the superimposed tone waves must be preserved. In particular it is necessary to faithfully preserve the relative intensities of 20 the various partial tones, because it is on this that the correct reproduction of the sound timbre depends.

To accomplish this the means used for translating and reproducing the amplified sound must not be affected by mechanical, 30 magnetic or electrical inertia. In particular, when using electric currents, it is necessary to obviate the occurrence of the disturbing effects of inductance because—especially 35 in cases in which the tone reproduction covers a large range of sound wave frequencies—self-induction alters the form of the current curve and thus destroys the proper reproduction of the tones.

40 The object of the invention is to radically remove all the aforesaid drawbacks and to provide means for reproducing tones without any change of timbre and with perfect distinctness, and at the same time to increase 45 their volume or loudness to such an extent that they can be heard well in all parts of any large hall.

It is well known that spoken words and musical sounds can be reproduced by means 50 of an electric arc by superimposing on the arc current the current fluctuations produced by means of a telephonic transmitter or the like. The electric arc is specially well adapted for the reproduction of tones, because it is an elastic body of air of very

high temperature whose volume fluctuates in accordance with the fluctuations of the current strength and therefore directly produces air sound waves.

A drawback of known electric arc sound 60 reproducing arrangements is that they are not capable of combining distinctness and purity of reproduction with a loudness that is sufficient for practical purposes, and this is the reason why the talking, singing and 65 musical arc has hitherto not been used for practical purposes.

In order to cause the arc lamp to satisfactorily reproduce the sounds it receives it is necessary to make the amplitudes of the current fluctuations superimposed on the arc current as great as possible and to transfer or translate them into the arc lamp circuit without occasioning any disturbing effects through self-induction. This is a condition 75 which none of the previously proposed arrangements has fulfilled.

By the present invention a device or arrangement is produced which, contrary to known arrangements, not only reproduces 80 all tones as loudly as necessary, but which does this entirely without distortion of the original tones.

This is accomplished (1) by causing the current fluctuations, corresponding to the 85 original tones and conducted through the arc lamp, to be produced by electric thermionic valves, whose grid potential is controlled or varied by a sound transmitter (in the broadest sense of the word) directly affected by the sound waves, or by a photoelectric cell or the like affected by a film on which the sounds are recorded in any suitable manner, and (2) by providing means for this purpose and for superimposing the 90 tone current fluctuations on the arc current through which means the translation of the said fluctuations is accomplished without interference by self-induction, and hence with 95out distortion. The original current fluctuations may first be superimposed on a high frequency current produced by a separate high frequency producer and the high frequency current whose wave form is thus determined by the said fluctuations may be 100 sent through the arc of an arc lamp supplied from a source of continuous current, or the said high frequency current affected by the fluctuations due to the original tones may itself be caused to produce an electric 105

110

arc in an alternating current arc lamp. If, for convenience of description, the original current affected by the telephonic transmitter, photo-electric or selenium cell or the like, be called the "voice current", then the problem being dealt with is to magnify or amplify the fluctuations of the voice current very considerably, but without distortion, and to render these amplified, undistorted current fluctuations audible by means of an electric arc. To solve this problem it is, as stated above, important to obviate all distortions by inertia due to mass, hysteresis etc., particularly in producing the voice current, and it is also important to make the fluctuations of the primary or original voice current as great as possible so as to be able to achieve the ultimate result with the smallest possible degree of amplification, or with the smallest possible number of amplifiers or amplifying steps. When it is a question of reproducing recorded sound waves, as waves recorded on a relief-film or phonographic record this can be accomplished by means of a discharge gap with an incandescent cathode influenced by the relief film, or, when it is a question of reproducing the actual sounds by transforming them into alternating electric currents that affect the electric arc, by means of telephonic condenser transmitters which are connected in parallel to a non-inductive resistance in the grid circuit of the high frequency producer.

The invention is illustrated by way of example in the drawing in which—

Fig. 1 shows an arrangement for reproducing sounds recorded in relief on a tape film whose wavy surface vibrates a style,

Fig. 2 shows an arrangement in which sound records on a tone film produce corresponding current fluctuations which are impressed upon high frequency currents, then amplified together with the high frequency current and finally superimposed by induction on a current flowing through an electric arc which reproduces the sounds,

Fig. 3 illustrates another modification in which the high frequency current upon which the tone frequency is impressed directly produces the sound emitting arc in an alternating current lamp.

In the arrangement shown in Fig. 1 the sound waves are recorded in relief on a film *f*, each prominence on the film corresponding to a crest of a sound wave and each depression on the film corresponding to a hollow between two sound wave crests. A bi-chromated gelatin relief film of this kind may be produced by a swelled-gelatin process, the gelatin being coated for example with a metallic or steel covering by electro-plating. A style or knife edge engages with the relief film *f*, the style or knife edge forming the extremity of the short arm pressed down towards the film by a spring *m*. The

short arm or feeler is connected with a longer arm *n* and adapted to swing around a pivot at the point where the short and long arm *n* meet. The long arm *n* of the feeler carries a small plate *a* at its free end, which is connected to a battery *b* from which it derives a high electrical potential. The plate *a* is the anode of a discharge gap in which an electrical discharge is caused to take place by the corresponding cathode *k* (oxide cathode) at the other side of the gap, being brought into incandescence by the heating battery *h*. The cathode *h*, when incandescent, ionizes the discharge gap. The incandescent cathode *k* is connected to the other pole of the battery *b* through a high non-inductive resistance *w* and also through parallel paths extending from the incandescent cathodes *k*¹, *k*², *k*³ of a number of thermionic valves *r*¹, *r*², *r*³ to the grids *g*¹, *g*², *g*³ of these valves. *a*¹, *a*², *a*³ are the anodes of the thermionic valves *r*¹, *r*², *r*³ . . . and *k*¹⁻³ is the heating battery for the incandescent cathodes *k*¹, *k*², *k*³. The valves *r*¹, *r*², *r*³ are connected in parallel to the electrodes of an arc lamp *o* which receives current from a battery of accumulators *p* through a resistance *q*. The regulating coil *s* of the arc lamp is a circuit which is independent of the shunt circuit formed by the thermionic valves. A choking coil *t* is connected in the arc lamp supply circuit so as to prevent the current fluctuations corresponding to the sound waves and sent through the arc from passing into the supply circuit and being thus weakened.

When the sound wave record or tone film *f* travels past the feeler *n*, motions are imparted to the latter which cause corresponding alterations of the gap between the anode *a* and the cathode *k*. Changes of resistance of the discharge gap are thus produced and result in corresponding fluctuations of potential in the grid circuits of the thermionic valves. By this means considerably amplified fluctuations of the current flowing through the thermionic valves connected in parallel to the arc are set up so that corresponding fluctuations of the arc lamp supply current are produced and the arc is caused to emit sound waves. The feeler *n* can be made so light that, at the speeds of oscillation which occur in translating sounds, no disturbances will arise from its inertia. As the resistance of the discharge gap is very great and can be made about equal to the resistance of the grid circuit, the fluctuations of potential produced at the grid are relatively considerable and a high efficiency is obtained. This arrangement thus represents a low-frequency current-fluctuation amplifier in which the grid potential is controlled without giving rise to distortion and without the aid of a transformer, and in which the cur-

rent fluctuations are very considerably amplified by simple means and then impressed upon the electric arc.

In the arrangement shown in Fig. 2 the current fluctuations corresponding to the tone frequencies are superimposed on a high frequency current. This is done for the purpose of enabling thermionic valves adapted for high potential and corresponding higher efficiencies to be used without deleterious inductive effects occurring when the necessary conversion or transformation of the voice currents of high potential to the lower voltages suitable for the electric arc is carried out. To accomplish this the periodicity of the high frequency current is not changed, but its amplitudes only are caused to fluctuate in the rhythm of the rates of vibration of the tones to be reproduced, and hence variations of phase and distortions of the sounds to be reproduced are obviated.

A source of light or an incandescent lamp filament P and a lens O are arranged so that a transparent film travelling at a uniform speed passes through a narrow streak of light. The light, whose intensity is weakened more or less according to the opacity of the parts of the film (which comprises cross lines of various degrees of transparency) through which it passes, impinges, after it is reflected by a mirror M arranged at an angle of 45°, upon a photoelectric cell Z (gas cell) consisting of a cathode K of sodium which is connected to the grid G¹ of a thermionic valve R¹, while the anode A of the photoelectric alkali-metallic cell Z is connected to the incandescent cathode K¹ of the valve R¹, a high resistance W¹ being also connected to the cathode K¹ in parallel with the anode A. The current sent from the battery B¹ through the circuit K, G¹, K¹, A is thus caused to fluctuate in accordance with the sound record on the film and these fluctuations cause corresponding fluctuations of potential at the grid G¹.

W¹ is a high non-inductive resistance in a by-path of the circuit leading through the photo-electric cell to the grid of the thermionic valve R¹.

A¹ and A² are anodes of thermionic valves R¹ and R². Current is supplied to the two valves R¹ and R² by a battery B² whose positive pole is connected to the anode A² of the valve R². In the lead from the battery B² to the anode A² there is an inductance S and a variable condenser C, the inductance and the condenser C forming an oscillating circuit coupled in a known manner to the grid G² of the valve R² by means of a coil S². By means of this arrangement undamped oscillations of high frequencies are produced in the high frequency circuit and the current fluctuations

corresponding to the sound waves are superimposed on these oscillations. The super-imposition of the sound wave frequencies takes place in the following manner:

The current fluctuations which are produced by means of the photo-electric cell Z affected by the travelling tone film F give rise to corresponding fluctuations of potential at the grid G¹ of the valve R¹, and these fluctuations in turn produce fluctuations of the anode current through the two valves R¹ and R² which correspond to the tone frequency. This gives rise to corresponding changes of the amplitudes of the high frequency oscillations whose periodicity, however, remains unchanged. Corresponding changes of the amplitude of the high frequency oscillations are produced hereby, but the rate of vibration of the oscillation remains unaltered. These high frequency oscillations, on which the tone frequencies are superimposed, are now amplified without the occurrence of inertia, in a known manner and to the extent necessary for obtaining the desired loudness, by means of the high frequency amplifier arrangement hereinafter described.

The undamped oscillations in the thermionic valve R², instead of being produced automatically, may be set up by an external exciting means consisting of a separate source of high frequency current. The "auto-excitation" of the thermionic valve by means of a reactive coupling can also be substituted by the dynatron circuit arrangement which is based on the utilization of the so-called declining characteristic.

The amplification of the high frequency carrier current which carries the tone frequency is accomplished in the following manner: Coupled with the coil S of the oscillation circuit I is a coil S³ which is included in a circuit that extends through the grid G³ and the incandescent cathode A³ heated by the heating battery H³ and arranged in the thermionic valve R³. The valve R³ is supplied with current by the battery B³ connected to the anode A³. Inserted between the battery B³ and the anode A³ is a coil S³ which carries the current flowing through the anode A³ and forms the primary coil of an ironless high frequency transformer T² that translates the high frequency current amplified by the valve R³ to the grid circuit of another thermionic valve R⁴. This translation is accomplished with the aid of the coil S⁴ which forms a secondary coil of a transformer G² and is included in the grid circuit of the valve R⁴. A potential, which is relatively high so as to correspond with the output of the valve R⁴, is thus applied to the grid G⁴ of this valve. Since the tone frequency is impressed on the high frequency oscillations at both sides of the zero line, a kind of vibration is produced

with which the current values above and below zero neutralize each other at each moment. It is therefore necessary to rectify the high frequency current and this is done in the following manner: The translation of the high frequency oscillations through the transformer T^1 to the valve R^3 and from this valve to the thermionic valve R^4 is carried out in such a way that at all times only one half, say the positive half, of the high frequency oscillations produce the fluctuations of potential at the grid, which are necessary for operating the valves. To this end an initial potential is applied to the grid, this initial or preliminary potential being negative or positive according to the characteristic of the valve and being of such magnitude that the point lying midway between the positive and negative crests of the high frequency oscillations lies at the lower or upper bend of the curve, which represents the characteristic of the thermionic valve, that is the curve that gives the values of the current in the anode circuit at different grid potentials and at a constant anode potential. By this means a rectifying effect is obtained which results in a high frequency pulsating uni-directional current being caused to flow in the anode circuits of the valves, the maximum values of this current corresponding to the impressed tone frequency. This rectifying method will, for convenience of description, be called the "anode method of rectifying at the bottom or top bend of the characteristic curve of the valve."

The anode circuit of the thermionic valve R^4 which receives current from the battery B^4 , contains the primary coil of a high frequency transformer T^2 , the secondary coil S^2 of which has a comparatively small number of turns. The high tension of the high frequency current of the last thermionic valve is thus stepped down to a potential corresponding to that of the electric arc, while its current strength is correspondingly increased.

The problem that now remains to be dealt with is to superimpose on the arc of a continuous current arc lamp the high frequency current of constant amplitude produced in the valve R^2 and which, after the tone frequency has been impressed upon it in the valve R^1 so as to give rise to changes of its amplitudes corresponding to the sound waves, has its amplitudes increased in the valves R^3 and R^4 without distortion of the original sound wave form. This is accomplished by connecting the secondary circuit of the high frequency transformer T^2 to the arc L of the arc lamp. This shunt across the arc is barred by means of a barrier in the form of a condenser C^2 against the flow of the continuous current sent through the arc lamp by the battery B^2 while the alternating current superimposed upon the continuous cur-

rent is prevented from entering the continuous current circuit by means of a choking coil D^2 . W^2 is a rheostat.

In the further modification of the invention shown in Fig. 3 the arc of an alternating current arc lamp is directly produced by the high frequency current upon which the tone frequency is impressed. The particular advantages obtained hereby are as follows:

As the arc is directly produced by, or supplied with, high frequency current the changes of amplitude of the high frequency current that correspond to the sound vibrations need only amount to a small percentage, as 10 per cent for example, of the normal amplitude of the high frequency current. Since the ratio between the fluctuations and the normal amplitudes in the different amplifying steps of the high frequency thermionic valves remains unaltered, it is not necessary to make this ratio any greater at the first step. Hence the fluctuations of the voice current conducted through the circuit in the first stage need only be very small. This facilitates the faithful or distortionless translation of the voice currents and also renders it possible to reproduce feeble sounds, or sounds coming from a considerable distance. Since the carrier current is a high frequency current the amplification is attained in the high frequency thermionic valve arrangement without distortion, there being no mass, inductance or hysteresis that can exert a distorting effect. Any desired degree of amplification can be obtained in the high frequency amplifier or thermionic valve. The alternating current arc lamp permits of a perfectly continuous and uniform regulation of the gap between its electrodes. By feeding the arc with high frequency alternating current the advantage of an "ascending characteristic" of the arc is obtained, that is to say the resistance of the latter, instead of representing a negative value as in ordinary arcs, becomes positive, and is therefore adapted in an increased degree for the faithful reproduction of tones of all kinds. The acoustic effect of the high frequency alternating current is considerably greater than that of a low frequency undulating unidirectional current for the following reasons:

The fluctuations of amplitude of the high frequency current that correspond to the sound waves are impressed on both sides (positive and negative) of the current curve. The fluctuations of current are therefore twice as great as in the case of a continuous current on which a voice current is superimposed. If electrodes or carbons placed at an angle to each other are used—which presents no difficulty in alternating current lamps in which the carbons are both

consumed at equal rates—the powerful magnetic field gives rise to very strong pulsations of the arc, and this helps in the production of the air waves that produce the sound. Another point to be noticed is that in a continuous current lamp the so-called commutator noises of the continuous current dynamo are difficult to eliminate from the reproduced tone, while the supply of continuous current from accumulators is generally not feasible for economical reasons.

In Fig. 3 an alternating current arc lamp arrangement is shown in which 1 is a thermionic valve with an anode 2 and an incandescent cathode, 3 that is heated by current supplied from a heating battery, 4 through a resistance 5 of iron. The high frequency current is produced in a known manner by means of an oscillation circuit comprising an adjustable condenser 6 and an inductance 7, and connected to the grid 8 of the valve 1 by a reactive coupling which comprises a potentiometer arrangement 46. The super-imposition of the tone frequency on the high frequency current, that is to say, the alteration of the amplitudes of the high frequency current in accordance with the ordinates of the sound wave curve, is accomplished by including a high non-inductive resistance 9 and one or more condensers 10 of comparatively small capacity in the one wire of the reactive coupling circuit. In each condenser one condenser-plate is constructed in the form of a diaphragm adapted to approach and recede from its associated plate in accordance with the sound vibrations. Each condenser thus constitutes a transmitter which is capable of faithfully reproducing the sound waves it receives, as it is not subject to the drawbacks of a contact or carbon microphone. The high frequency current produced in the high frequency circuit, and the tone frequencies impressed upon it, are translated by induction from the coil 7 to the coil 11 and thus conducted to the grid 12 of a thermionic valve 13. The amplified high frequency current is then translated by a coil 14 in the circuit of the anode 13 into the coil 15 which impresses corresponding fluctuations of potential on the grids 16 and 17 of two thermionic valves 18 and 19 connected in parallel. The anodes of the valves 18 and 19 are connected to an oscillatory circuit comprising an adjustable condenser 20 and an inductance 21, and, in order to obtain a high efficiency, this oscillatory circuit is tuned to the primary oscillatory circuit 6, 7. The high frequency current in the coil 21 induces a corresponding high frequency current in the coil 22, from which the induced current flows through the two electrodes or carbons 23, 24 of an alternating current arc lamp. In order to facilitate the tuning of the two oscillatory circuits 6, 7

and 20, 21 the couplings of all of the coils used for translating the high frequency current oscillations are loose. The arc lamp is regulated in a known manner by a regulating coil 26 in the main circuit and by a regulating resistance or rheostat 27. The electric arc 28, on receiving the high frequency current oscillations on which the tone frequencies are impressed, reproduces all the sound vibrations taken in at the receiving end by the diaphragms of the condenser microphone 10. The sound vibrations reproduced by the arc are considerably amplified and quite undistorted.

The entire high-frequency amplifier arrangements 1, 2, 21 may be supplied with current by a single alternating current machine 29 which produces currents of fairly high frequencies. This current is sent through an autotransformer 30 from which two circuits are branched off in accordance with the potentiometer principle, the one circuit comprising the wires 31, 32 and the other the wires 31, 33.

The circuit 31, 32 contains the transformer coils 34 and 35. The coil 34 induces a current in the secondary coil 35 for heating the incandescent cathode 36 of a Wehnelt rectifier 37 and the coil 35' induces current in a secondary coil 38 which heats the incandescent cathodes 39 and 40 of the two thermionic valves 18 and 19.

The circuit 31, 33 contains the primary coil 41 of a high frequency transformer which receives alternating current of a medium frequency. This current induces a corresponding current in the coil 42 which is conducted to the two anodes 43 and 44 of the rectifier 37. The coil 42 is tapped at the middle. The current stepped up to a high tension in the transformer 41, 42, and conducted through the rectifier 37, flows in the form of a continuous current from the cathode 36 through a wire 45, high resistance 46 and a wire 47 to the middle of the coil 42. Inserted in the wires 45 and 47 are choking coils 48 and 49. Large condensers 50 and 51 are connected across the wires 45 and 47 at both sides of the choking coils 48 and 49. The choking coils 48, 49 and the condensers 50 and 51 form a smoothening arrangement by which any remaining fluctuations of voltage are eliminated and the current made perfectly continuous.

The thermionic valves 1, 13, 18 and 19 are supplied with current from the resistance 46 on the potentiometer principle through wires 52 and 53, 54 and 55, 56 respectively.

The arrangement to which the invention relates is primarily intended for reproducing vocal and musical notes in cooperation with films in moving pictures theatres, the sound records being made to travel synchronously with the cinematographic picture film. The invention is, however,

also adapted for transmitting to a distance speeches and vocal and instrumental performances which may be telephonically transmitted from a central point to any 5 distant places in each of which the original sounds may be made audible to a large gathering and faithfully reproduced.

According to the manner in which the novel arrangement is used, the electric arc 10 must be entirely or partly screened off, and this must be done without interfering with the ventilation of the arc lamp. An artificial ventilation of the lamp is preferred, because this enhances the acoustic effect. The devices used for screening off the light will 15 preferably be such that the sound waves reach the auditorium by indirect reflection. An arrangement of this kind consisting of an upper conical opaque hood 57 and of a bottom conical opaque cup or basin 58 20 is shown in Fig. 3, and a similar device is also illustrated in Figs. 1 and 2.

I claim:—

1. In an arrangement for electrically reproducing sounds, a thermionic valve, means 25 for converting sound waves into corresponding electric fluctuations and for impressing these fluctuations on the grid of the thermionic valve, and an electric arc affected by the anode circuit of the thermionic valve, 30 said arc being connected in parallel to the said anode circuit.

2. In an arrangement for electrically reproducing sounds, a thermionic valve, means 35 for converting sound waves into corresponding electric fluctuations and for imparting these fluctuations to the grid of the thermionic valve, an electric arc affected by the anode circuit of the thermionic valve, and two hollow conical screens for screening off 40 the light of the arc and reflecting the sound waves emitted by it in the direction of the axes of the conical screens.

It testimony whereof I have signed this specification.

OTTO BOTHE.
